SIMULATED SPACE GUN OR SIMILAR ARTICLE

Ronald W. Zick, Torrance, Calif., assignor to Jamison, Inc., Torrance, Calif., a corporation of California

Filed May 1, 1967, Ser. No. 6,915

Term of patent 14 years

(Cl. D34—15)

FIG. 1.

FIG. 2.

FIG. 3.

FIG. 4.

FIGURE 1 is a side elevational view of a simulated space gun or similar article, illustrating my new design;

FIGURE 2 is a top plan view of a simulated space gun or similar article, illustrating my new design;

FIGURE 3 is a front elevational view of a simulated space gun or similar article, illustrating my new design; and

FIGURE 4 is a rear elevational view of a simulated space gun or similar article, illustrating my new design.

The side opposite that shown in FIGURE 1 is substantially identical therewith.

The broken lines in the drawing represent supports for the simulated space gun.

I claim:

The ornamental design for a simulated space gun or similar article, as shown and described.
